BALING PRESS

Orion Thomas Quinn, Sr., Los Angeles, Calif., assignor, by mesne assignments, to Apex Steel Corporation, Ltd., Los Angeles, Calif., a corporation of Nevada

Application December 31, 1946, Serial No. 719,474

5 Claims. (Cl. 100—19)

1

This invention pertains to a baling press adapted to compress waste paper, cotton waste, rags, cork chips, metal cuttings, scrap metal and various other materials into consolidated or compressed bales which are then strapped or bound in the usual manner. The invention is specifically directed to improvements in baling presses, among such improvements being simple and efficient means for opening and closing the upper portion of the charging box so as to permit the charging box to be readily filled and the pressed material readily removed from the press.

The invention is also directed to an improved type of door and door-locking mechanism in the upper portion of the press, the door-locking mechanism being interconnected with the hydraulic system which operates the main pressure-applying platen so that the door-locking pressure is correlated to the maximum pressure being employed in compressing the material within the press.

In addition, the invention relates to an improved construction relating to the upper or ordinarily stationary head against which the material is compressed. In accordance with this invention, means are provided for moving the head into and out of position over the end of the charging box and such head-moving means are interconnected with the main hydraulic system which operates the primary pressure platen.

Ordinarily, a baling press consists of a vertical charging box into which the material to be compressed is placed. In most instances the head of the charging box is stationary. A portion of the well of the charging box is made removable, constituting a door through which the material to be compressed may be admitted. Various usual means for holding the door in position involved wing nuts, lag bolts, and the like, and a considerable amount of time was consumed in opening and closing the door and in making certain that the door would hold against the internal pressure of the material during compression.

The usual stationary head, moreover, made it impossible to fill the box from an upper level. The present invention contemplates a movable head which permits material to be charged directly through the end of the charging box, the head then moving into position across the end of the box during compression of the material.

In addition, the invention contemplates a simplified control assembly or system whereby the various operations are easily controlled, a single source of fluid pressure actuating the ram, the

2

door-locking means, and the head-moving means. Furthermore, the preferred hydraulic system employs the static head of the ram and bale in positively releasing the head-moving means and in releasing the door-locking mechanism.

It is an object of the present invention, therefore, to disclose and provide an improved baling machine.

A further and more specific object of the invention is to disclose and provide novel and efficient door means and door-locking means for the charging box of a baling press.

A still further object is to disclose and provide a baling press provided with an hydraulically operated movable head.

These and other objects and advantages of the present invention will become apparent to those skilled in the art from a detailed description of an illustrative embodiment in which the inventions have been incorporated. In such description, reference will be had to the appended drawings, in which:

Fig. 1 is a front elevation of the entire baling press.

Fig. 2 is a side elevation thereof.

Fig. 3 is a schematic, isometric piping diagram of the pressure fluid actuating system.

Fig. 4 is a horizontal section taken approximately along the plane IV—IV of Fig. 1, showing the doors in closed position.

Figs. 5 and 6 are horizontal sections taken on broken line VI—VI of Fig. 7 illustrating the position of the parts with the doors open and closed, respectively.

Fig. 7 is a side elevation of the door-closing mechanism, portions thereof being broken away.

Fig. 8 is a plan view of the movable head.

Fig. 9 is a side elevation of the head showing the position of the parts while a bale is being compressed.

Fig. 10 is a side elevation of the head in normal position.

Fig. 11 is a side elevation of the head when it has been moved away from the charging box.

Fig. 12 is a transverse section taken along the plane XII—XII of Fig. 10.

Figs. 13 and 14 are sections through the hydraulic means which actuate the head, showing the position assumed by the parts when the head is in open and in closed positions, respectively.

As best shown in Figs. 1 and 2, a baling press is generally positioned between floors of a building or with a large portion of the press within a pit having side walls. The main body of the press is termed a charging box and includes the

front, back and side walls, such as 2 and 3, suitably reinforced to withstand internal pressures. This charging box, generally indicated by the numeral 4, is open at the bottom. In the embodiment shown, the press includes corner posts 5 supported upon a base 6 and extending upwardly into a hollow head, generally indicated at 7. This hollow head or head frame is connected to the base 6 as by means of long tie rods 8 nested within the corner posts or corner columns 5.

Movably positioned within the charging box 4 is a pressure platen 10 mounted upon the end of a piston 11 working within a cylinder 12. In the drawings, the cylinder 12 is shown provided with an outer protective casing 13. The piston 11 and cylinder 12 will be hereafter referred to as the hydraulic ram which actuates the pressure platen 10 and compresses the material charged into the box 4 against a head closing the upper end of the charging box and similarly closing the hollow head frame 7.

At an appropriate level, such as the floor level indicated, the sides of the box 4 are provided with doors. In the instant case the front of the press may be provided with a lowermost door section 15 hinged at 16 and provided with suitable hand-operated locking devices at 17. The main door of the press is indicated generally at 20 and both the front and back of the press are preferably provided with such doors 20 and 21.

By referring to Fig. 4 it will be noted that the doors 20 and 21 are hingedly connected to the framework of the charging box as at 22 and 22' and each of the doors consists of a main or front panel and an end portion lying in a plane transverse to the main panel. These end portions 23 and 23' are provided with outwardly extending lips 24 and 24', these lips being capable of virtually meeting or contacting when the doors are closed (as in Figs. 4 and 6). It will be understood that the doors may be suitably reinforced to withstand internal pressures and may be provided with handles 25 and 25' to facilitate manual opening thereof.

In order to hold the doors in closed position, a pair of dogs 26 and 26' is pivotally mounted as upon trunnions or vertical pins 27 and 27' adjacent the end portion of said doors when said doors are in closed position. Means are provided for causing these dogs 26 and 26' to partially rotate so as to engage and press against the lips 24 and 24', thereby holding the doors 20 and 21 in locked position. Such means are preferably hydraulic and may include a working cylinder 28 containing a piston (not shown) mounted upon the piston rod 30.

The piston rod may carry a crosshead 31 and links 32 and 32' pivotally mounted thereon, these links being pivotally connected to arms 33 and 33' (as at 34 and 34'), the arms being connected to the dogs 26 and 26'. It will be evident that movement of the piston and piston rod 30 will therefore cause partial rotation of the dogs, the links 32 and 32' and arms 33 and 33' virtually forming a toggle to prevent the release of the doors when the doors are in closed position (see Fig. 6). It will be noted from an examination of this last-named figure that the links 32 and 32' are substantially on dead center so that a positive movement of the piston and piston rod 30 is required to unlock the doors.

It will be evident that unless a head were provided so as to close the hollow head frame 7, any material charged into the box 4 would be

lifted by the pressure platen 10 through the hollow head frame 7. A movable head is provided, this head being generally of C shape in side elevation.

As best seen in Fig. 10, this movable head assembly consists of a lower and main head member 36 and an upper frame 37, the head and frame being held in spaced relation as by means of downwardly extending and interconnecting members 38. Extending rearwardly from the hollow head frame 7 are spaced tracks 39 and a centrally disposed track or arm 40. The frame 37 is provided with wheels 41 adapted to run along the tracks 39 and a wheel 42 arranged to run along the arm 40.

The entire movable head may therefore run along the tracks 39 and 40 from the position indicated in Fig. 11 to the position indicated in Fig. 10. In the closed position (Fig. 10) the head member 36 covers the entire aperture within the hollow head frame 7 and is immediately above the upper edges of the doors 20 and 21. In order to facilitate such movement, hydraulic means are provided, such means including the working cylinder 43 carried by the frame 37. Positioned within the working cylinder 43 is a piston 44 (Fig. 13) attached to a tubular piston rod 45. Although various forms of hydraulic cylinder construction may be employed, the exemplary form includes an outer tubular piston rod element 46 also attached to the piston 44.

The outer end of the arm 40 may be provided with an upstanding track 47 having a slot 48 therein, said slot receiving a transverse pin carried by the tubular member 46 so as to prevent the compound piston rod composed of elements 45 and 46 from moving longitudinally and still permitting such end to move vertically within the slot 48, for reasons which will become apparent hereafter.

A single hydraulic system and a simplified method of controlling the system permit operation of the various elements described hereinbefore. The hydraulic system may be best understood by reference to Fig. 3. As there shown, oil (or other fluid) from a reservoir or surge tank 50 is pumped by pump 51 through a relief valve 52 and pressure conduit 53 into the lower end of working cylinder 12 of the ram. The conduit 53 includes a check valve 54 so as to prevent flow of pressure fluid from the working cylinder 12 back into the pump. The relief valve 52 permits the pump 51 to recirculate the oil through line 55 whenever excessive pressure is built up in line 53.

A pair of pumps may be used, one pump 51 being capable of generating pressure up to say 500 pounds per square inch, while the other, such as 51', may generate pressures up to 2000 pounds per square inch. Both pumps, however, discharge into the working cylinder, pump 51' feeding into the working cylinder through pressure conduit 53'.

Pressure conduit 53 is connected to line 56 at 65 a point between the working cylinder 12 and the check valve 54. The line 56 communicates with line 57 leading to a four-way control valve 60. A branch line 58 connects lines 56 and 57 with reservoir 50 but is separated therefrom by means of a valve 61. The valve 61 is normally closed.

When the four-way control valve 60 is in operating position, pressure fluid supplied by line 57 is discharged from the valve through line 62. Line 62 branches, one of the branches, 63, lead-

ing to working cylinder 28 of the door-locking mechanism. The other branch, 64, is connected to the central hollow piston rod 45 of piston 44 in working cylinder 43 of the movable head. When, therefore, the pumps are started so as to compress material placed into the charging box (as by punching start buttons on a control panel P), pressure fluid is sent by line 53 into the bottom of the working cylinder 12 of the ram and simultaneously fluid pressure is sent by lines 56 and 57 through the control valve 60. When the valve is in closed or operating position, fluid pressure is discharged from the valve by line 62 into lines 63 and 64, thereby causing the piston in working cylinder 28 to move outwardly, thereby rotating the dogs 26 and 26' from the position shown in Fig. 5 into the locking or hold position of Fig. 6. Simultaneously, pressure fluid supplied by line 64 to hollow piston rod 45 is discharged into the forward end of working cylinder 43. Since the piston rod 45 can not move longitudinally, the working piston itself, together with the entire movable head frame to which it is attached, moves from the position shown in Fig. 11 to the position indicated in Fig. 10. Fluid contained in the rear or outer end of working cylinder 43 is discharged therefrom as through port 65 into the annular space between hollow rod 45 and tube 46, and returns to the system via line 66 to line 67 and control valve 60, from whence it is discharged by line 68, the latter being connected to return line 58.

Simultaneously, liquid on the opposite side of the piston in working cylinder 28 is returned to the system by line 69 which is attached to return line 67.

Since the pressure necessary to move the head and frame 36 and 37, and the door-locking mechanism is relatively low (in comparison with the pressure necessary to actually raise and compress the material within the charging box 4), the head will roll into position and the doors will be locked before the ram 12 has risen to any appreciable extent. As the material within the charging box is more fully compressed and high pressures develop within the working cylinder 12 of the ram, greater pressure is similarly exerted in the working cylinders 28 and 43. The doors, therefore, are maintained in closed position more firmly as the waste is compressed.

It is to be understood that while the charging box is being filled, the doors 15, 20 and 21 are open and the movable head is in the open position. Material may be placed within the charging box either from dollies and dumped through the open sides or doors of the charging box, or it may be admitted into the charging box through the hollow head frame 7. After a sufficient quantity of material has thus been placed into the charging box, the lower doors 15 (which are optional) are manually closed. The doors 20 and 21 are closed almost completely by hand, and then the hydraulic system is energized to cause the simultaneous operation of the ram, door-locking means and head-moving means as previously described.

After the material has been thoroughly compressed it will be found that such material has raised the head member 36 a short distance into pressure contact with the hollow head frame 7 as indicated in Fig. 9, wherein the upper edge of the baled, compressed material is indicated at 70. Such upward movement of the head member 36 has also caused the head frame 37 to be lifted. The pumps are then stopped and

valve 61 is opened. Pressure within the hydraulic system is relieved and some of the pressure fluid is discharged from the working cylinder 12 by line 56, valve 61, and return line 58, back into the reservoir 50. The piston 11, together with the pressure platen 10, slowly drops and as soon as pressure on the bale 70 has been relieved in this manner and before the pressure platen 10 drops below the level of the charging floor, the valve 61 is again closed. Fluid lines 56 and 57 now carry the static head of the ram and the bale positioned upon the pressure platen 10. This static pressure is employed in rolling the head back and in unlocking the doors by moving the control valve 60 into open position. Static pressure fluid continues to enter the valve 60 through line 57 but is now discharged from the valve by line 67 into branch lines 66 and 69 connected with working cylinders 43 and 28 respectively, causing the doors to unlock and the head to roll back. Excess fluid from the working cylinders 43 and 28 is returned by lines 64 and 63 respectively to line 62 and valve 60, from whence such fluid is discharged by line 68 into return line 58. After the doors have been opened and the bale removed, valve 61 is again opened, permitting the ram to descend to the bottom of the charging box.

It is to be understood that at any suitable time the material of the bale may be banded or bound. A separate valve may be inserted in line 64 or 66, as at 71 or 72, to prevent the head from being rolled back until the doors have been opened.

35 Numerous changes and modifications may be had in the system and obviously not all of the novel elements of the invention need be employed at the same time. All changes and modifications coming within the scope of the appended claims are embraced thereby.

I claim:

1. In a baling press including a charging box and a pressure platen movable therein, the combination of: movable doors at the upper end of the charging box; a head movable into and out of position over the end of the charging box; hydraulic ram means for moving the pressure platen; hydraulically actuated head-moving means; hydraulic door-locking means; a pressure pump connected to a reservoir; a pressure fluid conduit including a check valve connecting said pump with the ram means; and a pressure fluid line including a control valve connecting said conduit, at a point between the check valve and ram means, with said head-moving means and door-locking means, said control valve selectively controlling the direction of movement of the head-moving and door-locking means.

2. In a baling press including a charging box and a pressure platen movable therein, the combination of: movable doors at the upper end of the charging box; a head movable into and out of position over the end of the charging box; hydraulic ram means for moving the pressure platen; hydraulically actuated head-moving means; hydraulic door-locking means; a pressure fluid line for supplying fluid pressure to the head-moving and door-locking means to hold the same in head-closed and door-locked position; and means for supplying pressure fluid from the ram means to the head-moving and door-locking means to open the head and unlock said doors.

3. In a baling press including a charging box and a pressure platen movable therein, the com-

bination of: movable doors at the upper end of the charging box; hydraulic door-locking means; a hydraulic ram means for moving the pressure platen; a pressure pump connected to a reservoir; a pressure fluid conduit including a check valve connecting said pump with the ram means; a pressure fluid line connecting said conduit at a point between the check valve and ram means for supplying pressure to the door-locking means to hold the same in door-locked position; and means for supplying pressure fluid from the ram to the door-locking means to unlock said doors when the pump is inoperative.

4. In a hydraulic bailing press provided with a charging box, a pressure platen movable in said box, and hydraulic means for moving the pressure platen, the provision of: a pair of doors at the upper end of the charging box, said doors being mounted for movement about vertical axes and arranged to form an extension of two sides of the charging box when in closed position; a hollow head frame above said doors and in virtual alignment with the walls of the charging box; track means extending from the hollow head frame; a C-shaped head assembly including a lower head

15 20 25

member and an upper frame; said head member and frame being held in spaced relation; wheels on the upper frame in alignment with said track means; and means for moving the head assembly along the track means from a position wherein the lower head member bridges the hollow head frame to a position wherein the lower head member is external of the hollow head frame.

5. A hydraulic baling press of the character stated in claim 4, wherein the head assembly moving means is hydraulically operated and interlocked with the hydraulic means for moving the pressure platen.

ORION THOMAS QUINN, SR.
